FILAMENT SUPPORT

Filed Sept. 3, 1918

Inventor:
Sigurd Thronsen.
by *J. Roberto* Atty

UNITED STATES PATENT OFFICE.

SIGURD THONSEN, OF CHICAGO, ILLINOIS, ASSIGNOR TO WESTERN ELECTRIC COMPANY, INCORPORATED, OF NEW YORK, N. Y., A CORPORATION OF NEW YORK.

FILAMENT SUPPORT.

Application filed September 3, 1918. Serial No. 252,379.

To all whom it may concern:

Be it known that I, SIGURD THONSEN, a citizen of the United States, residing at Chicago, in the county of Cook and State of Illinois, have invented certain new and useful Improvements in Filament Supports, of which the following is a full, clear, concise, and exact description.

This invention relates to electron discharge devices and has for its object to provide a means whereby the filament therein may at all times be kept under the proper degree of tension to prevent vibration thereof. This invention is particularly applicable to electron discharge devices of the audion type where other parts, closely related to the filament, are contained within the evacuated space, and where absence of vibration is necessary not only to lengthen the life of the filament but as well to maintain the space relation between the filament and the other electrodes, upon the maintenance of which depends the proper functioning of the device.

The invention is illustrated in the drawing which represents an electron discharge device employing my invention.

As shown, the device comprises a base portion 1 adapted to be inserted in a suitable socket, not shown. To this is attached in evacuated glass container 2. The usual glass press or electrode support 3 is shown, from which leading-in wires extend to the various parts. Plate electrodes 4, 5 are shown, the top portions of which are connected and adapted to retain a block 6 of suitable insulating material.

Grids 7 and 8 of suitable mesh are shown and are supported by wires 9 and 10 extending from the insulating block 6. A filament 11 is shown of any suitable material and is supported at its upper end by a wire 12 extending from the under part of the junction between the upper ends of plate electrodes 4 and 5. The lower ends of the filament 11 are connected to leading-in wires 13 and 14 of any suitable material. These wires are bent into suitable shape and form a spring means whereby the tension of the filament is maintained at the proper degree under all conditions of temperature. The planes of

plates, grids, filament and filament spring supports 13 and 16 are parallel.

Looking at the tube from the right of the figure it will be seen that the left-hand leading-in wire 14, which extends from the glass portion 3 nearer to the left-hand lower end of filament 11, is bent further to the left in the form of a curved bow and then extends to the right and at its other end is connected to the right-hand lower end of the filament. Similarly, the right-hand leading-in wire 13, which extends from the glass portion 3 nearer to the right-hand lower end of filament 11, is bent further to the right in the form of a curved bow and then extends to the left and at its other end is connected to the left-hand lower end of the filament. The bowed portion of the leading-in wires provides spring tension and the long arm of the wire extending from the bowed portion to the lower end of the filament provides a lever arm sufficient to keep the filament taut under all degrees of expansion and contraction thereof.

It is therefore evident that the life of the filament is considerably lengthened due to absence of short-circuiting with other electrodes which might be produced by vibration, and that the device functions properly because the space relations, upon which its proper operation depends, are maintained constant. What is claimed is:

1. An electric device comprising a filament, a rigid support therefor and means to tension said filament comprising a pair of resilient wires, each wire being provided with a return bend portion and having one of its ends connected with said filament.

2. An electric device comprising a filament, a rigid support therefor, resilient lead wires for said filament, each lead wire being provided with a return bend portion and having one of its ends connected to said filament.

3. An electric device comprising an evacuated vessel, a base therefor, a filament, a filament support arising from said base portion, means to tension the filament comprising a pair of resilient wires arising from said base portion, said wires being provided with approximately opposed bow portions,

the free ends of said wires overlapping each other and being attached to said filament.

4. An electric device comprising an evacuated vessel, a base portion therefor, a plurality of electrodes comprising a filament therein, a support for said electrodes arising from said base portion, resilient lead wires for said filament arising from said base por-

tion, said wires having approximately opposed spring bow portions, the free ends of 10 said wires overlapping each other and being attached to said filament.

In witness whereof I hereunto subscribe my name this 26th day of August, A. D. 1918.

SIGURD THRONSEN.
